SELF-SUSTAINING SCAFFOLD

Robert K. Squire, Los Angeles, Calif.

Application May 15, 1948, Serial No. 27,250

2 Claims. (Cl. 304—2)

1

The present invention relates to scaffolds particularly useful in the performance of work upon buildings and other structures.

An object of the invention is to provide an improved scaffold, which is of simple, safe and sturdy construction, and which can be erected or dismantled with ease in a minimum of time.

Another object of the invention is to provide a scaffold structure, which can be made of sections of substantially uniform or standard size, permitting the structure to be erected to various heights or lengths without the necessity for altering or modifying the individual sections or the components of each section.

A further object of the invention is to provide a scaffold structure which can be erected to the desired height by readily superimposing and clamping scaffold sections to one another.

This invention possesses many other advantages, and has other objects which may be made more clearly apparent from a consideration of a form in which it is embodied, which is shown in the drawings accompanying and forming part of the present specification. This form will now be described in detail, illustrating the general principles of the invention; but it is to be understood that this detailed description is not to be taken in a limiting sense, since the scope of the invention is best defined by the appended claims.

Referring to the drawings:

Figure 1 is a partial isometric view of superimposed scaffold sections clamped to one another;

Fig. 2 is an enlarged fragmentary end elevation, looking in the direction of the arrow 2 on Fig. 1, with a part in section; and

Fig. 3 is an enlarged cross-section, taken along the line 3—3 on Fig. 2.

The scaffold structure disclosed in the drawings includes a plurality of end sections 10, which may be superimposed upon one another to reach a desired height, and which may also be placed longitudinally at spaced intervals from one another, to obtain a scaffold structure of any desired length. Each end section includes a pair of spaced uprights or vertical studs 11, such as wooden 2 x 4's or 4 x 4's, which are held in spaced relation by a horizontal cross structure 12. The structure 12 includes a horizontal member 13 having ends welded to oppositely directed vertical clamp members 14, of similar channel cross-section, which are adapted to embrace the inner portions of the uprights 11. The cross structure 12 may be further strengthened by

2

diagonal braces 15 suitably secured, as by welding, to the horizontal cross member 13 and to the channel members 14.

Each end of the cross structure 12 is rigidly secured to the uprights 11 by disposing another vertical clamp member 16, of generally channel cross-section, on the other side of the uprights, and facing the channel member 14 welded to the cross member 13 and to the diagonal brace 15. The opposed channel members 14, 16 embrace the upper end of the upright 11, and have a bolt 17 extending through the webs 18 of the vertical channels 14, 16, which, upon being tightened, serves to clamp the upright 11 securely to the horizontal structure 12. By thus clamping each horizontal structure 12 to the spaced vertical uprights 11, a scaffold section 10 is formed.

Another scaffold section or end is made in the same fashion, and may be spaced longitudinally from the section just described. Of course, it is preferred that the cross structures 12 be of equal length, in order to provide a uniform spacing between the uprights 11 at each section of the scaffold. The end sections 10 may be attached to one another in longitudinally spaced relation by use of a longitudinal member 19 of wood, or any other suitable material, that is nailed, bolted or otherwise suitably secured to the longitudinally spaced uprights 11 at one or both sides of the scaffold structure. If desired, the outer channel iron members 16 may be secured to one another by a horizontal, longitudinal bar 20, which may be in the form of an angle iron whose vertical flange 21 is welded to the outer sides 18 of the channel irons 16.

A platform 22 may be placed upon and across the cross bars 13, and may be constituted by several planks of wood, or other suitable material, having the desired combined width to enable a workman to stand safely elevated above the ground, or other support.

Other scaffold sections may be superimposed upon the lower section. The upper vertical studs 11a are of essentially the same uniform length and size as the lower studs 11, and may be inserted between the opposed channel irons 14, 16 to an extent in which their lower ends 11b are adjacent the clamp bolt 17. Tightening of the bolt 17 will not only serve to secure the transverse structure 12 to the lower uprights 11, but also to the lower ends of the upper uprights 11a.

As disclosed in the drawings, four vertical uprights 11a have been clamped to the four corners

of the lower scaffold structure. Another set of transverse members 12a and channel iron clamps 14a, 16a may be placed on the upper end of the vertical studs or uprights 11a, which have been secured in the lower clamps 14, 16, in the same fashion as the lower clamps have been attached to the uprights 11 therebelow. Vertical studs 11b may be secured in these upper clamps 14a, 16a. A scaffold structure can be built up in this manner by superimposing uprights 11, 11a, 11b, etc., one upon the other, securing the adjacent upper and lower ends of the uprights to the intervening clamps 14, 16; 14a, 16a; etc., with the transverse members 12, 12a, etc., holding the vertical upright structure in appropriate spaced relation.

As stated above, the vertical studs 11, 11a, 11b are preferably all of substantially the same length and of the same cross section, the distance between the flanges 22 of each channel iron element 14, 16, 14a, 16a preferably being only slightly greater than the thickness or width of the stud which they embrace. The cross-section of the studs will, of course, depend upon the loads that they are to carry. As an example, the uprights 11, 11a, 11b may be made of 2" x 4" or 4" x 4" wood studs, with the adjacent ends of the studs securely clamped by appropriately tightening the bolts 17, 17a, etc. Such tightening creates sufficient friction between the studs and the channel iron members as to prevent slipping therebetween. That is to say, the lower ends of the upper studs need not necessarily rest upon the clamp bolt 17, the vertical load being transmitted from an upper stud 11a through the channel iron clamp members 14, 16 to the lower stud 11.

For the purpose of facilitating assembly, the outer channels 16 and longitudinal bar 20 may have holes 23 through which nails 24 may be driven into the studs 11, 11a, 11b. The studs may thus be held in appropriate spaced relation while the clamp bolts 17 are being tightened.

It is apparent that a scaffold structure has been provided which can be readily assembled to any desired height, simply by superimposing vertical studs upon one another, with the adjacent ends of the studs effectively secured to one another by means of the channel iron clamps. In addition, the scaffold may be made of any desired length merely by spacing the end supports 10 appropriately with respect to each other, and securing longitudinal members 19, or 20, or both to the studs or vertical uprights. The structure is simple and sturdy, and possesses a high degree of safety.

It can be dismantled very readily, and then reassembled whenever and wherever desired.

I claim:

1. In a scaffold structure: a series of spaced pairs of uprights forming rectangularly arranged lower vertical posts; a second series of spaced

5 pairs of uprights forming rectangularly arranged upper vertical posts; said upper posts being adapted to be superposed on said lower posts respectively; an elongate brace member between each of said pair of uprights; said brace members each having integrally formed inner clamp members at each end thereof, said inner clamp members having post engaging surfaces contacting aligned lateral surfaces of said superposed posts respectively; outer clamp members cooperating with each of said inner clamp members respectively, said outer clamp members having post engaging surfaces contacting the opposite aligned lateral surfaces of said superposed posts respectively; and means extending through said inner and outer clamp members and interposed between the cooperating ends of said superposed posts for spacing said upper and lower posts and for clamping said posts between said clamp members.

2. In a scaffold structure: a series of spaced pairs of uprights forming rectangularly arranged lower vertical posts; a second series of spaced pairs of uprights forming rectangularly arranged upper vertical posts; said upper posts being adapted to be superposed on said lower posts respectively; an elongate brace member between each of said pair of uprights; said brace members each having integrally formed inner clamp members at each end thereof, said inner clamp members having post engaging surfaces contacting aligned lateral surfaces of said superposed posts respectively; outer clamp members cooperating with each of said inner clamp members respectively, said outer clamp members having post engaging surfaces contacting the opposite aligned lateral surfaces of said superposed posts respectively; means extending through said inner and outer clamp members and interposed between the cooperating ends of said superposed posts for spacing said upper and lower posts and for clamping said posts between said clamp members; and means secured to said outer clamps of adjacent pairs of uprights for holding said pair of uprights in spaced relationship.

ROBERT K. SQUIRE.
